UNITED STATES PATENT OFFICE

WILLIAM B. STOUT, OF DETROIT, MICHIGAN

DESIGN FOR A FUSELAGE FOR AIRPLANES

Original application filed May 11, 1931, Serial No. D—39,815. Divided and this application filed June 22, 1931. Serial No. 40,295. Term of patent 14 years.

To all whom it may concern:

Be it known that I, WILLIAM B. STOUT, a citizen of the United States, residing at Detroit, in the county of Wayne and State of Michigan, have invented a new, original, and ornamental Design for a Fuselage for Airplanes, of which the following is a specification, reference being had to the accompanying drawings, forming a part thereof, this application being a division of copending ap-

plication Serial No. D—39,815, filed May 11, 1931.

Figure 1 is a side elevation and

Figure 2 is a front elevation, showing my new design.

I claim:

The ornamental design for an airplane fuselage, as shown.

WILLIAM B. STOUT.
